UNITED STATES PATENT OFFICE.

FRED W. KAMMERER, OF NEW YORK, N. Y.

WEATHER STRIP.

Application filed April 5, 1924. Serial No. 704,323.*

My invention relates to weather strips, and more particularly to metal interlocking weather strips, as applied to casement windows, French-doors and the like, one element 5 of which is attached to the window or door and the other to the sill, and both interlocking as a protection against the weather when the door or window is closed.

In the drawings:—

10 Fig. 1 is a transverse section of a casement window to which my invention has been applied;

15 Fig. 2 a perspective view of the member which is attached to the sash, and

15 Fig. 3 a similar view of the member attached to the window sill.

Referring to the drawings in detail, the window-sill is indicated at 4 and the sash at 5. The sill member is indicated in whole at 20 A, and is attached to the sill by screws as at 6. This sill member A comprises the base portion 7 and two side walls 8 and 9. The side wall 8 has an inwardly extending flange 10. The side wall 9 is higher than the opposite side wall 8, and it also has an inwardly extending flange indicated at 11. The bottom of the sash 5 is rabbeted so as to snugly fit over and upon the sill member A and also to accommodate the sash member which is indicated in whole at B. The sash member B consists of a flat metal strip 12 attached to the outside of the sash by nails 13, and right-angle portion 14, the latter being bent upon itself to form a channel to take the inwardly extending flange 11.

35 Preferably this portion of the sash member is resilient, so as to have a spring action pressing upon each side of inwardly extending flange 11, without jambing thereon. For the purpose of securing such an effect, the bent portion 11' is made relatively thinner than the loose end 11". The latter is bent upon itself as at 11', which gives it a sliding

movement when engaging the inwardly extending flange 11, similarly to its action if it were bevelled.

What I claim is:—

1. In a device of the class described, a sill member having a base and two side walls, each of different height, the higher wall having an inwardly extending flange, and a sash member comprising an attaching strip having a right-angled portion, the latter being bent upon itself to form a substantially U-shaped channel, to springingly engage both upper and lower faces of the inwardly extending flange of said sill member.

2. In a device of the class described, a sill member having a base and two side walls, each of different height, the higher wall having an inwardly extending flange, and a sash member comprising an attaching strip having a right-angled portion, the latter being bent upon itself to form a substantially U-shaped channel, to springingly engage both upper and lower faces of the inwardly extending flange of said sill member, so that the free end thereof shall extend approximately to the inner side of the higher wall of the sill member.

3. In combination with a sash and a window sill, a sill member having a base and two side walls, each of different height, said walls having inwardly extending flanges, and a sash member comprising an attaching strip having a right-angled portion, the latter being bent upon itself to form a substantially U-shaped channel, to springingly engage both upper and lower faces of the inwardly extending flange of said sill member, said sash having two rabbets, the inner rabbet to take and abut the lower side wall of the sill member, and the outer rabbet to take and abut the higher side wall of the sill member.

FRED W. KAMMERER.
